United States Patent [19]

Kikuta et al.

US00D332602S

[11] Patent Number: Des. 332,602

[45] Date of Patent: ** Jan. 19, 1993

[54] ELECTRICAL CONNECTOR COVER CASE

[75] Inventors: **Shigeru Kikuta; Yoshikazu Hirata**,
both of Tokyo, Japan

[73] Assignee: **Hirose Electric Co., Ltd.**, Tokyo,
Japan

[**] Term: **14 Years**

[21] Appl. No.: **670,773**

[22] Filed: **Mar. 18, 1991**

[30] Foreign Application Priority Data

Sep. 17, 1990 [JP] Japan 2-30896

[52] U.S. Cl. **D13/154; D13/147**

[58] Field of Search D13/146, 147; 439/345,
439/368, 597, 625, 660, 727

[57] CLAIM

The ornamental design for an electrical connector cover case, as shown and described.

DESCRIPTION

FIG. 1 is a perspective view of an electrical connector cover case showing an embodiment of our new design; FIG. 2 is a side elevational view thereof, the other side being a mirror image;

FIG. 3 is a bottom plan view thereof;

FIG. 4 is a rear elevational view thereof;

FIG. 5 is a top plan view thereof; and,

FIG. 6 is a front elevational view thereof.

FIG. 1

FIG. 2

FIG. 3

FIG. 4

FIG. 5

FIG. 6
